CLAIM

I claim the ornamental design for a blackhead remover, as shown and described.

DESCRIPTION

FIG. 1 is a Perspective view of a blackhead remover showing my new design;

FIG. 2 is a front view thereof;

FIG. 3 is a back view thereof;

FIG. 4 is a right-side view thereof;

FIG. 5 is a left-side view thereof;

FIG. 6 is a Top view thereof;

FIG. 7 is a Bottom view thereof;

FIG. 8 is another Perspective view with a different head;

FIG. 9 is yet another Perspective view with another head; and,

FIG. 10 is yet another Perspective view with another head. The broken lines depict portions of the blackhead remover that form no part of the claimed design.

1 Claim, 10 Drawing Sheets
